(57) **CLAIM**

The ornamental design for a blade for a sickle, as shown and described.

DESCRIPTION

FIG. 1 is an isometric view of the first embodiment of a blade for a sickle, showing the design.

FIG. 2 is the first side elevational view of a blade for a sickle thereof;

FIG. 3 is the second side elevational view of a blade for a sickle thereof;

FIG. 4 is a front elevational view, enlarged for ease of illustration, of a blade for a sickle thereof;

FIG. 5 is the rear elevational view of a blade for a sickle thereof;

FIG. 6 is the top plan view of a blade for a sickle thereof; and FIG. 7 is the bottom plan view of a blade for a sickle thereof. FIG. 8 is an isometric view of the second embodiment of a blade for a sickle, showing the design.

FIG. 9 is the first side elevational view of a blade for a sickle thereof;

FIG. 10 is the second side elevational view of a blade for a sickle thereof;

FIG. 11 is the front elevational view, enlarged for ease of illustration, of a blade for a sickle thereof;

FIG. 12 is the rear elevational view of a blade for a sickle thereof;

FIG. 13 is the top plan view of a blade for a sickle thereof; and FIG. 14 is the bottom plan view of a blade for a sickle thereof. FIG. 15 is an isometric view of the third embodiment of a blade for a sickle, showing the design.

FIG. 16 is the first side elevational view of a blade for a sickle thereof;

FIG. 17 is the second side elevational view of a blade for a sickle thereof;

FIG. 18 is the front elevational view, enlarged for ease of illustration, of a blade for a sickle thereof;

FIG. 19 is the rear elevational view of a blade for a sickle thereof;

FIG. 20 is the top plan view of a blade for a sickle thereof; and FIG. 21 is the bottom plan view of a blade for a sickle thereof. FIG. 22 is an isometric view of the forth embodiment of a blade for a sickle, showing the design.

FIG. 23 is the first side elevational view of a blade for a sickle thereof;

FIG. 24 is the second side elevational view of a blade for a sickle thereof;

FIG. 25 is the front elevational view, enlarged for ease of illustration, of a blade for a sickle thereof;

FIG. 26 is the rear elevational view of a blade for a sickle thereof;

FIG. 27 is the top plan view of a blade for a sickle thereof; and FIG. 28 is the bottom plan view of a blade for a sickle thereof.
